CLAIM

The ornamental design for a facial recognition device, as shown and described.

DESCRIPTION

FIG. 1 is a front perspective view of a facial recognition device showing our design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings illustrate portions of the facial recognition device that form no part of the claimed design.
